UNITED STATES PATENT OFFICE

2,188,860

REFRIGERATOR CAR FLOOR RACK

Garth G. Gilpin, Riverside, Ill., assignor to Standard Railway Equipment Manufacturing Company, Chicago, Ill., a corporation of Delaware

Application April 19, 1939, Serial No. 268,742

5 Claims. (Cl. 105—375)

The invention relates to insulated refrigerator cars used to transport perishable commodities, such as vegetables, fruits, berries, meats, eggs, frozen fish, etc., and to maintain such commodities while in transit within a predetermined range of temperature, thus necessitating the use of a refrigerant in the summer and a heating means in the winter. It has been found that perishable commodities which have not been allowed to get too cold (freeze) or too hot (bake) have a high market value because they have a longer storage life.

The invention relates specifically to "floor racks" for such refrigerator cars which comprise a foraminous or perforated floor, arranged to support the lading in the car in spaced relation to the insulated floor of the car so that air, after it has been cooled by a refrigerant, or heated by a heater, may pass under the lading and through the foraminous floor and up through or between the lading.

Recent improvements in refrigerator car design have resulted in the use of the so-called top bunker car. Cars of this type have the refrigerant containers suspended below the roof and are commonly provided with flues associated with the side walls. These flues conduct refrigerated air from the refrigerant containers to the space under the floor rack.

An object of the invention is to provide means to prevent or retard movement of the lading during service movements of the car. Service movements are defined as the accelerating, decelerating and sudden starting and stopping to which a railway car is subjected during ordinary operation of a railway train. The movements tend to shift the lading toward one end of the car; to overcome this tendency I provide a floor rack having transversely extending slats on the upper surface thereof.

Another object is to provide means by which the refrigerated air from the side wall flues may circulate below all portions of the lading.

Other objects and advantages of my invention will be apparent from the following detailed description taken in reference to the drawing in which:

Figs. 1 and 2 are transverse and longitudinal sections respectively of a refrigerator car embodying my invention.

Fig. 3 is a perspective view of my floor rack.

In the refrigerator car shown in Figs. 1 and 2, the essential parts shown are roof 2, side walls 3, end wall 4, floor 5, refrigerant containers 6, flues 7 associated with the side walls 3, hatches 8 and

floor rack 9. The lading is shown in broken lines 10. The arrows 11 show the path followed by the refrigerated air from the containers 6 downwardly through the flues 7, under the rack 9 and thence upwardly through the lading compartment. 5

The floor rack 9 comprises a plurality of spaced apart slats 20 extending laterally of the car. The slats 20 are supported by a plurality of spaced apart slats 21 extending longitudinally 10 of the car. The slats 20, 21 are supported by laterally disposed stringers 23. The stringers 23 divide the space under the rack 9 into a plurality of ducts 25 extending transversely of the car and communicating with the flues 7. Cold air from the flues 7 may then flow through the ducts 25, the spaces between the slats 21 and the spaces between the slats 20 to the lading compartment of the car. The edges 27 of the slats 20 offer resistance to movement of the lading longitudinally of the car, thus retarding shifting of the lading due to service movements of the car. 15

The accompanying drawing illustrates the preferred form of the invention, though it is to be understood that the invention is not limited to 25 the exact details of construction shown and described, as it is obvious that various modifications thereof, within the scope of the claims, will occur to persons skilled in the art.

I claim:

1. In a refrigerator car, the combination of a foraminous rack for supporting a lading above the floor and means associated with the side walls of the car to induce an air current in the space below said rack, said rack comprising means to divide said space into a plurality of ducts communicating with said first mentioned means, and spaced apart slats extending transversely of the car to retard movement of the lading toward the end walls of the car. 30

2. In a refrigerator car, the combination of a foraminous rack for supporting a lading above the floor and means associated with the side walls of the car to induce an air current in the space below said rack, said rack comprising means to divide said space into a plurality of ducts communicating with said first mentioned means and extending transversely of the car, and spaced apart slats also extending transversely of the car to retard movement of the lading toward the end walls of the car. 40

3. In a refrigerator car, the combination of a foraminous rack for supporting a lading above the floor and means associated with the side walls of the car to induce an air current in the space 55

below said rack, said rack comprising transversely disposed spaced apart stringers which divide said space into a plurality of ducts communicating with said means, and spaced apart slats also extending transversely of the car to retard movement of the lading toward the end walls of the car.

4. In a refrigerator car, the combination of a foraminous rack for supporting a lading above the floor and means associated with the side walls of the car to induce an air current in the space below said rack, said rack comprising transversely disposed spaced apart stringers which divide said space into a plurality of ducts communicating with said means, spaced apart slats also extending transversely of the car to retard movement of the lading toward the end walls of the car, and means to support said slats upon said stringers.

5. In a refrigerator car, the combination of a foraminous rack for supporting a lading above the floor and means associated with the side walls of the car to induce an air current in the space below said rack, said rack comprising transversely disposed spaced apart stringers which divide said space into a plurality of ducts communicating with said means, spaced apart slats also extending transversely of the car to retard movement of the lading toward the end walls of the car, and means to support said slats upon said stringers, said last mentioned means comprising spaced apart slats supported by said stringers and extending transversely thereto and to said first mentioned slats.
